his Attorney,

UNITED STATES PATENT OFFICE.

GEORGE C. KERR, OF BRAINERD, MINNESOTA, ASSIGNOR OF ONE-HALF TO WM. H. HERRMANN, OF BRAINERD, MINNESOTA.

REFRIGERATOR.

1,278,165.

Specification of Letters Patent. Patented Sept. 10, 1918.

Application filed August 10, 1916. Serial No. 114,179.

To all whom it may concern:

Be it known that I, GEORGE C. KERR, a citizen of the United States, residing at Brainerd, in the county of Crow Wing and 5 State of Minnesota, have invented certain new and useful Improvements in Refrigerators, of which the following is a specification.

My invention relates to refrigerators and 10 has for its object to provide a refrigerator formed of two shells of concrete one within the other, the inner shell having cast in it a tubular coil through which a cooling liquid may be circulated to cool the interior of the 15 device.

A further object is to form the inner shell so as to just pass through the opening in the outer shell to provide a suitable dead air space, the joint between the two 20 shells being sealed from without. A still further object is to form a tight joint between the coil terminal and the outer shell, to which end I provide a hollow boss formed on the interior of the outer shell which 25 comes in contact with the inner shell and registers with the coil terminal. Through this hollow boss a pipe connection may pass and be coupled to the coil terminal, the space about said connection and the boss 30 being sealed up similar to the joint between the shells, thus securely embedding the pipes in both shells and forming a perfectly tight air space.

A still further object is to connect my 35 refrigerator to a water supply system so as to permit all of the water used in the system for ordinary purposes to pass through the refrigerator for cooling the same or to pass by it, as desired.

40 The full objects and advantages of my invention will appear in connection with the detailed description thereof and are particularly pointed out in the claims.

In the drawings, illustrating the application 45 of my invention in one form,—

Figure 1 is a perspective view of my improved refrigerator showing the external appearance of the same. Fig. 2 is a plan sectional view of the device with some parts 50 cut away, showing the arrangement of the pipes forming the cooling coil. Fig. 3 is an elevational sectional view taken substantially on line 3—3 of Fig. 2. Fig. 4 is an enlarged detail view of a portion of the 55 refrigerator shown in Fig. 2.

As clearly shown in the drawings, my invention comprises two independent shells or members 10 and 11 which are formed separately and assembled to provide a dead air space 12 almost completely surrounding shell 10 on three sides. Shell 10 is preferably rectangular, having a bottom and top 13 and 14, end walls 15 and 16 and a single side wall 17, being open at the other side. Within the top and bottom 13 and 14 and 60 the end walls 15 and 16 is embedded a tubular coil formed of vertical pipes 18 and 21 and horizontal pipes 19 and 20 connected continuously together with suitable pipe fittings. At the unions of pipes 18 and 20, 70 which occur at the bottom of shell 10, a number of T-fittings 22 are provided which have one of their openings positioned in alignment with pipes 20 flush with the exterior of wall 15 for a purpose to be later 75 explained. At the extreme ends of the coil, pipes 19 and 20 are provided with coupling fittings 23 which also come flush with the exterior of wall 16. The exposed ends 24 of the walls 13, 14, 15 and 16 are provided 80 with an angle iron 25 securely anchored in the concrete and extending perimetrically about the opening in member 10 for serving as a door frame.

Shell 11 is formed similar to shell 10 but is 85 of larger dimensions to provide the air space 12 previously referred to and comprises a top and bottom 26 and 27, end walls 28 and 29 and a single side wall 30, being open at the opposite side. Along this opening is 90 formed a lip 31 which extends completely about the same and which is of a size just large enough to permit of inserting the shell 10 into the space within shell 11. At the corners of shell 11, and at other positions, 95 are arranged a number of blocks 32 which may be formed separate or may be cast integral therewith for supporting the inner shell 10 and for holding the same in place. Lip 31 may be formed if desired with a 100 slightly oblique edge which, as will be noted, faces the outward flanges of the angle iron member 25 on shell 10. When the shell 10 is correctly positioned within shell 11 the joint between the two, which occurs at the 105 edge of lip 31 and angle iron 25, is sealed with cement, tar, pitch, sulfur or some other suitable substance at 38, rendering the joint air-tight.

The manner of bringing the pipe connec- 110

tions through the shell 11 can best be comprehended from Figs. 3 and 4. A hollow lug or boss 33 is formed on the interior of shell 11 to register with each of the various 5 openings in the pipe fittings exposed in the shell 10 and comes up flush with the walls of member 10 when the same is in place. The holes in bosses 33 extend completely through them and the respective walls of 10 shell 11 and are considerably larger than the pipes of the coil or the fitting thereof. After the shell 10 is secured in place a nipple 34 is inserted through boss 33 and screwed into the fitting exposed. The space about 15 said nipple and boss 33 is then sealed at 37 similarly to the joint between the two members, rendering the space 12 absolutely airtight.

In Figs. 1 and 4 can best be seen the door 20 construction. I preferably employ two doors 35 and 36 formed of concrete within an angle iron casing 39. These doors are hung within the frame formed by the angles 25 and may be provided with double glazed windows 40 25 and 41 if desired. It will be comprehended that the doors or any other portion of the refrigerator may be reinforced if found necessary, though the walls through which the pipes extend being somewhat thicker than 30 the other walls will not need any such expedient. When the refrigerator is to rest upon the ground I provide feet 42 which are bolted to the member 11 before the assemblage of the device.

35 The method of connecting the coil to the water-supply main and the operation of the device are explained as follows. The free ends of the coil are connected to a pair of valves 43 and 44 which are brought out one 40 above the other by means of a pipe 45 extending horizontally from either of the coil terminals to the corresponding valve. These valves are further connected by suitable fittings to a vertical pipe 46 which has interposed in it a valve 47 positioned between valves 43 and 44. By this arrangement all 45 of the water passing through the supply pipe can be caused to flow through or by the refrigerator at will. When valve 47 is closed and valves 43 and 44 open, water entering either end of pipe 46 will flow through the coil and out of the other end of this pipe. When the closure of the valves is reversed the water will pass directly through 50 pipe 46 without entering the coil. To prevent the water within the coil from freezing when the refrigerator is left in a relatively cold place during the winter, I provide a number of cocks 48 attached to the T-fittings 55 60 65 22, one for each convolution of the pipe, by means of which the coil may be perfectly drained. To effect this valves 44 and 47 are closed and the valve 43 and the cocks 48 temporarily opened. When the water is out valve 43 is closed and valve 47 opened, which

permits the water to be used for ordinary purposes without passing through the refrigerator.

Although my refrigerator is especially adapted to be used in conjunction with ordinary water-supply systems, the same will operate equally well with any of the cooling systems now in use. By coating the exterior and interior of the device with enamel paint or a similar substance the refrigerator 70 can withstand water or dampness and will be found to be absolutely sanitary, as there are no pockets or crevices exposed in which food substances can lodge.

I claim:

1. A refrigerator comprising an inner and an outer shell of moldable material separated from each other by an air space, a cooling-liquid circulating coil embedded within said inner shell, and connections with 85 said coil for maintaining a flow of cooling liquid therethrough from outside the refrigerator.

2. A refrigerator comprising a casing, a coiled pipe embedded within the casing passing about the top and bottom and the ends of the casing and having its extremities issuing from diagonal corners of one end thereof, a pipe connected with one of said coil ends and extending along the case to a 90 point in vertical alinement with said other coil end, a vertical feed pipe communicating with both of said coil ends, valves in the connections to said coil ends adjacent said vertical pipe for cutting the coil in or out 100 of communication with said vertical pipe, and a valve interposed in said vertical pipe for causing the cooling fluid to flow through the coil or directly through said pipe.

3. A refrigerator comprising a casing, a 105 coiled pipe embedded within the casing passing about the top and bottom and the ends of the casing and having its extremities issuing from diagonal corners of one end thereof, a pipe connected with one of said coil ends and extending along the case to a point in vertical alinement with said other coil end, a vertical feed pipe communicating with both of said coil ends, valves in the connections to said coil ends adjacent said vertical pipe for cutting the coil in or out 110 of communication with said vertical pipe, a valve interposed in said vertical pipe for causing the cooling fluid to flow through the coil or directly through said pipe, and means for draining the coil when it is desired to have the water flow directly through 115 said water-supply pipe.

4. A refrigerator comprising an inner shell of concrete having a cooling-liquid 125 circulating coil embedded in the walls thereof, an outer shell of larger dimensions than said inner shell having a lip extending around the edge of one side forming an opening through which said inner shell may 130

just be passed, means for supporting the inner shell within the outer shell in conjunction with said lip, and pipe connections passing through said outer shell and communicating with said coil for supplying the cooling medium from outside the refrigerator.

5. A refrigerator comprising an inner and an outer shell of moldable material separated from each other by an air space, a cooling liquid circulating coil embedded within said inner shell, each end of said coil extending outwardly through said shells, a pipe connected with one of said coil ends and extending along the outer shell to a point in vertical alignment with the other coil end, a vertical feed pipe connected with the latter coil end and with the end of said pipe which is

10

15

in vertical alignment therewith, a valve in each of said connections, a valve in said vertical pipe between said connections, two hollow bosses formed interiorly of one end wall of said outer shell through which the coil ends pass, a plurality of hollow bosses formed interiorly of the other end wall of said outer shell, nipples connected with said coil and extending out through said bosses and cocks on the outer ends of said nipples.
